CORRELATIVE THERMOSTATIC SWITCH
MECHANISM

George W. Crise, Columbus, Ohio, assignor to
Crise Electric Manufacturing Company, Co-
lumbus, Ohio, a corporation of Ohio

Application September 18, 1943, Serial No. 502,962

3 Claims. (Cl. 200—138)

This invention relates to an improved thermostatically actuated switch mechanism for controlling electrical circuits, having particular reference to that type of switch mechanism embodying deflectable bimetallic elements which alter in position in response to varying surrounding temperatures.

It is an object of the present invention to provide a thermostatic switch wherein is embodied a casing having an axially disposed support adapted for the reception of one end of a spiral bimetallic coil, the outer or deflectable end of the coil being connected with a flexible reed member carrying spaced contacts, the latter being disposed for registration with complementary contacts supported by the casing, the arrangement being such that as the coil responds to variations in temperature, the contacts of the flexible reed member are progressively brought into or out of engagement with the casing carried contacts to effect the opening or closing of associated electrical circuits.

It is another object of the invention to provide a circuit-controlling system in which a pair of correlated switch units of the character set forth are provided, the two units being disposed in zones in which different temperature conditions usually prevail, and, wherein the bimetallic coil of one unit deflects in responding to temperature variations in a manner opposite to that of the coil in the other unit, the complementary casing carried contacts of the two units being electrically united, so that when the reed member contacts of both units are in engagement with complementary casing carried contacts, an electrical circuit containing said units and associated equipment is closed or energized.

While the thermostatic switch apparatus comprising the present invention may be employed in many different capacities, one of its uses is that of controlling the operation of the motors of ventilating fans, particularly the so-called attic type of fan now widely used in ventilating residential buildings.

At present, it is customary to control the motor of such a ventilating fan by means of a manual switch or through a clock operated switch. A unique problem is involved in effecting proper control of an attic fan because of the fact that its function is different from any other cooling device, since, for most effective operation, it must rely on drawing cool air from the outside into the house after there has been a drop in the outside temperature, such as usually occurs at night.

Obviously, the fan should be run only when

the house is too warm for comfort and then only if the outside temperature is lower than that inside the house. It is further obvious that these conditions occur under different weather conditions at different times of the day and night, which makes the use of a time or clock-controlled switch generally unsatisfactory and, of course, the manual switch, like any other hand control requires an understanding operator to obtain correct operation as well as the continued presence of the operator.

In its adaptation to attic fan control, the present invention employs two similar but novel thermostatic switch units which operate in conjunction with each other, one of the switch units being placed in an outdoor location and the other within the house containing the fan, the units being of such construction that when the outdoor temperature falls below that prevailing within the house, the motor circuit of the fan is completed. When the indoor and outdoor temperatures are substantially equivalent, the motor circuit will be opened, and if the indoor temperature rises above that prevailing out of doors, the motor circuit will likewise be completed. By this arrangement, the fan operates whenever such operation is advantageous, and, conversely, remains inactive when no need exists for its operation.

30 A further understanding of the invention may be obtained by referring to the following description and the accompanying drawing, wherein:

Fig. 1 is a diagrammatic view, partly in section, of the thermostatic switch apparatus comprising the present invention;

35 Fig. 2 is a transverse sectional view taken on the plane indicated by the line II—II of Fig. 1.

Referring more particularly to the drawing, there is disclosed at A a thermostatic switch unit adapted to be located outside the house in a protected position, said unit consisting of a circular casing 5 formed from insulating material and having a back wall 6, an annular side wall 7 and a removable front wall 8, the latter being provided with one or more openings for the ventilation of the interior of the casing.

40 Mounted axially within the casing 5 is a supporting post 9, the end portions of the post being rotatably received within bearing-affording openings formed in the back and front walls 6 and 8, respectively. Secured to the post 9 is one end of a spiral bimetallic coil 10, the latter having its high expanding metal on the outside of the spiral, so that the coil unwinds as it cools. 45 The outer or deflecting end of the coil has fas-

tened thereto, by means of a block 11 and a rivet 12, one end of a flexible spring steel reed 13, the opposite end of said reed being connected by means of a rivet and insulating block 14 with the inner surface of the annular casing wall 7. The reed carries at spaced intervals a plurality of contacts indicated at 15a, 15b, 15c, 15d and 15e which are movable with the reed in response to temperature induced deflection of the coil 10.

Disposed in registration with the contacts 15a to 15e, inclusive, is a series of casing carried contacts designated at 16a, 16b, 16c, 16d and 16e which, in this instance, comprise adjustable screws threaded into openings formed at intervals in the annular wall 7. The inner ends of the contacts 16a to 16e, inclusive, are positioned so that they may be progressively engaged or disengaged by the reed contacts 15a to 15e as unwinding or winding movement is imparted to the coil 10 as a result of temperature variations. The operating range of the thermostat may be varied by connecting with one end of the post 9 a manually movable indicator hand 17. The pointer, at the outer end of this hand, is movable over a graduated surface 18 provided at one side of the front wall 8 contiguous to its peripheral edge.

A supplemental thermostatic switch unit B is used in connection with the unit A but occupies an indoor location. The construction of the unit B is the same as that of the unit A, with the exception that its spiral thermostatic coil 10b has its high-expanding metal on the inside of the coil, so that the latter unwinds as it warms. Also, the graduations and markings 18b of the unit B are reversed in order with respect to the graduations and markings 18a of the unit A.

The reed 13b of the unit B also carries spaced stationary contacts 20a, 20b, 20c, 20d and 20e which are adapted for successive and progressive engagement or disengagement with the inner ends of stationary but adjustable contacts 21a, 21b, 21c, 21d and 21e carried by the annular wall of the casing.

The contacts 16a and 21a of the units A and B are united by a conductor 22a; the contact 16b is united with the contact 21b by a conductor 22b; the contact 16c with the contact 21c by a conductor 22c; the contact 16d with the contact 21d by a conductor 22d; and the contact 16e is electrically united with the contact 21e by a conductor 22e. In this instance, the post 9 of the unit A is united by a conductor 23 with the electric motor 24 of a ventilating fan 25, the latter being shown as mounted in an opening 26 extending through an attic flooring, whereby when the fan is in operation, vitiated air may be withdrawn from the lower floors of a building and discharged to the atmosphere through the opening 26 and other associated vents (not shown). A conductor 27 extends from the motor 24 to a source of electrical energy 28, such as a commercial house circuit, while another conductor 29 extends from the source 28 to the post 9b of the unit B.

In the operation of the apparatus, it will be noted that the inside thermostatic unit B has its bimetallic coil 10b wound with the high-expanding metal on the inside of the coil, hence, the coil 10b unwinds as the ambient temperature increases, thereby causing the reed contacts 20a to 20e, inclusive, to engage in consecutive and progressive order the casing contacts 22a to 22e, inclusive. It will also be noted that the flexible reed in each thermostatic unit and the contacts

carried thereby are connected through the fan 25 with the source of power so that whenever any of the contacts of the reed 13 is connected to a contact of the reed 13b, the fan circuit will be completed.

As shown in the drawing, the screw contacts 16c, 16d and 16e are in engagement with the contacts of the reed 13, and the contacts 16a and 16b are out of engagement with their respective reed contacts 15a and 15b. However, the fan circuit is incomplete since the contacts 21c, 21d and 21e are out of engagement with their respective reed contacts.

This condition would be typical of an ordinary 15 evening just before operation of the fans should start, with both outside and inside temperatures about 80° F. As the outside temperature continues to fall, the thermostatic unit A will close the contacts 15b and 15b, which will complete the circuit through conductor 22b, contacts 20b and 21b to the source of current supply, starting the fan. As the fan operates, cool air from the outside will cool the house slowly and the inside thermostatic unit, in response to such a temperature drop, will respond to break the circuit through contacts 20b and 21b. This will stop the fan unless a continued drop in outside temperature results in cooling the thermostatic unit A to such an extent that engagement is effected between the contacts 15a and 16a.

Under these circumstances, the fan would continue to operate through contacts 20a and 21a of the unit B, such operation being sustained until a further drop in house temperature flexes 35 the coil 10b and moves its associated reed 13b to break engagement between the contacts 20a and 21a. This minimum temperature may be selected by setting the pointer of the indicator 17b to any desirable temperature, for example 75° F., 40 so that the fan would remain idle until the next day, when a rise in temperature would reestablish the contacts 20a, 21a, 20b and 21b, 20c and 21c, 20d and 21d and 20e and 21e in their order, depending on how warm the day developed to be.

The fan, however, would not start because the thermostatic unit A, being outside, would warm more quickly than the inside unit B, and to break the correspondingly connected contacts comprising the groups indicated at 15 and 16 in the same order and at temperatures selectable by the adjustment of the hand 17. However, a sudden cooling of the outside, such as the result of a thunder shower, would reestablish the contacts 16a to 16e, inclusive, so that the operation of the fan would start as soon as the outside temperature fell below the house temperature, regardless of the time of day, but providing the inside temperature was above 75° F. or other selected temperature.

Consideration of the above will disclose that my improved thermostatic control system takes advantage of every opportunity to bring cool outside air into the house but always precluding fan operation when the outside air is too warm to be beneficial and likewise arresting fan operation whenever the interior temperature of the house is at a comfortable level.

I claim:

70 1. A thermostatic switch comprising a casing having an internal substantially circular chamber, an axially arranged post carried by said casing, a spiral thermostatic coil deflectable in response to temperature variations, said coil being 75 positioned in said casing chamber and having its

inner end fixed to said support, an arcuate flexible reed having one end secured to the outer deflectable end of said coil and its other end stationarily secured to said casing, a plurality of spaced contacts carried by said reed, and a plurality of spaced complementary contacts carried by said casing in registration with the reed contacts, the casing contacts being progressively engaged or disengaged by the reed contacts upon predetermined variations in the temperature around the coil.

2. A thermostatic switch comprising a casing, an axially arranged post carried by said casing having a substantially circular chamber, a spiral thermostatic coil deflectable in response to temperature variations, said coil being positioned in said casing chamber and having its inner end fixed to said support, an arcuate flexible reed having one end secured to the outer deflectable end of said coil and its other end stationarily secured to said casing, a plurality of spaced contacts carried by said reed, a plurality of spaced complementary contacts carried by said casing in registration with the reed contacts, the casing contacts being progressively engaged or disengaged by the reed contacts upon predetermined

variations in the temperature around the coil, and manually operated means accessible exteriorly of the casing for rotatably adjusting said post to vary the operating positions of the coil and the reed, whereby to control the temperature range at which said contacts are brought into and out of relative engagement.

3. A thermostatic switch comprising a casing having an inner chamber formed with an annular outer wall, an axially arranged rotatably adjustable support carried by said casing and positioned axially of said chamber, a spiral thermostatic coil deflectable in response to temperature variations, said coil being positioned in said chamber and having its inner end fixed to said support, an arcuate flexible reed having one end secured to the outer deflectable end of said coil and its other end secured to the inner peripheral wall of said chamber, and a plurality of spaced radially arranged contacts carried by the peripheral wall of said casing in registration with said reed, said contacts being progressively engaged by the reed upon predetermined variations in the temperature around said coil.
